UNITED STATES PATENT OFFICE.

JOSEF KOHOUSEK, OF BUDAPEST, AUSTRIA-HUNGARY.

KEYHOLE-GUARD.

SPECIFICATION forming part of Letters Patent No. 784,947, dated March 14, 1905.

Application filed March 12, 1904. Serial No. 198,085.

To all whom it may concern:

Be it known that I, JOSEF KOHOUSEK, engineer, residing at 55 Margit körút, Budapest, in the Empire of Austria-Hungary, have invented a new and useful Keyhole Guard or Closing Device, of which the following is a specification.

This invention relates to a keyhole guard or closing device—that is to say, to a safety device for blocking the keyhole—so that after the said device has been introduced into the keyhole and locked it is no longer possible to introduce another key and to open the lock or to obtain a wax impression of the keyhole for the purpose of forging a key.

Such devices mainly consist, as is well known, of a safety-lock of the shape corresponding to that of the keyhole, said lock after having been opened by means of a special key being introduced completely into the keyhole in such manner that after it has been locked it cannot be withdrawn by means of another key or any other object or pushed in or turned in the hole. The key of the lock can be withdrawn from the keyhole when the lock is open only together with the whole device. The keyhole of the device serving to receive the key is always inaccessible, so that an imitation of this key cannot be forged.

The safety-lock used in this keyhole-closing device consists according to this invention of a keyhole-guard, consisting of a housing having substantially the form of the bit and adjacent parts of the stem of the lock-key, a latch mounted to slide in said housing and adapted to be projected out at the back of the stem opposite the bit, a movable member mounted in the front of the bit part of said housing and suitably coupled to the said latch, the adjacent end of the stem part of the said housing being bored and slotted to receive a key, and means in connection with the said movable member for operating it to project the latch by means of the inserted key, together with other novel features appearing more fully hereinafter and recited in the appended claims.

In the accompanying drawings, Figure 1 shows a device according to this invention in section in open position—that is to say, in

which it can be introduced into the keyhole. Fig. 2 is a right-hand side view of Fig. 1. Fig. 3 is a section of the device similar to that in Fig. 1 with the key withdrawn in closed position. Fig. 4 is a front elevation of Fig. 1 with the casing inclosing the lock omitted. Fig. 5 is a section on the line 5 5 of Fig. 1. Fig. 6 is a front elevation similar to that in Fig. 4 with the tumblers partly removed in closed position. Fig. 7 is a section similar to 60 that in Fig. 5 on the line 7 7 of Fig. 3. Fig. 8 shows in side elevation the device introduced into the keyhole with the door and door-lock casing in section. Figs. 9 and 10 show, respectively, a front elevation and section 65 similar to Figs. 6 and 3 of a construction of the device according to this invention with a rotating disk instead of a slide.

As will be seen from the drawings, the device consists of a cylindrical bolt 1, corresponding in diameter to the stem of the door-key, and of a rectangular block 2, connected to it. The latter is intended to receive the locking device and is provided with a casing 4, Fig. 1, which fits exactly into the opening of the escutcheon or plate 3, covering the keyhole, Fig. 8. At one end the bolt 1 is provided with a central bore for receiving the key 5 and with a longitudinal slot 7, Fig. 4, for the introduction of the key-bit 6, the slot 7 being continued at the bottom by a transverse slot 8, Fig. 1, for the purpose of enabling the key to be turned. The bolt 1 is provided in the middle with an opening, such as the I-shaped opening shown in Fig. 2, and in the said opening is adjustably mounted a latch 9. One arm 9' of the latch 9 extends into a recess in the block 2 and is provided on its surface with an oblique or cam groove 10, with which engages a pin 12, secured to the bottom of a slide 11, guided in dovetail grooves in the block 2. Instead of the slide 11 guided in dovetail guides a disk 11, rotatably mounted in the block 2, could be used, as shown in Figs. 9 and 10. The slide or the disk 11 is 95 provided laterally with a recess 13, with which the key-bit engages when turned for the purpose of shifting or turning the slide or the disk 11. For insuring safety, however, the slide or the disk can move in the usual man-

ner, fixed tumblers 14, of which the drawings show, by way of example, only two, though of course any desired number could be used, by means of the correspondingly-shaped key-bit 6 against the action of the springs 17, pressing the lateral wall of the recess 15 of the tumblers 14 against the pin 16 of the slide or of the disk 11. Owing to this rectilinear movement of the slide or to the turning of the disk 11, the pin 12 of the latter will move in the cam-groove 10, Fig. 5, of the latch 9 and bring the latter, according to the direction in which the key is turned, into the open or closed position. (Shown in Figs. 1, 3, or 10.)

In the position of rest the latch 9 is in the position shown in Figs. 3 and 10—that is to say, the projection 9² of the latch 9 projects from the surface of the bolt 1. Then the key 5 can be freely introduced into the safety device, Fig. 6. By turning the key 5 the projection 9² of the latch 9 is completely withdrawn in the manner described into the transverse opening in the bolt 1, Fig. 1. Then the device can be easily introduced into the key-hole to be locked; but the key 5 cannot for the present be withdrawn from the device, as the bit 6 is no longer opposite the slot 7. By turning the key the device is locked in the interior of the keyhole, Fig. 8, and after the projection 9² of the latch 9 has engaged behind the cover-plate 18 of the door-lock casing, and thus become fixed, the key 5 can be withdrawn, the device itself remaining in the key-hole, Fig. 8, thus preventing the opening of the door-lock from either side. When the key 5 is again introduced and correspondingly turned, the projection 9² of the latch 9 is withdrawn in the manner described into the interior of the bolt 1, and the device can then be removed by means of the key-bit 6, which is then in the transverse slot 8. In order to insure still better the safety device against turn-

ing, the front end of the block 2 is provided with a pin 19, engaging in a hole in the lower part of the cover-plate 18 of the door-lock 45 casing.

What I claim, and desire to secure by Letters Patent of the United States, is—

1. A keyhole-guard consisting of a housing, having substantially the form of the bit and adjacent parts of the stem of the lock-key, a latch mounted to slide in said housing and adapted to be projected out at the back of the stem opposite the bit, a movable member mounted in the front of the bit part of said housing and suitably coupled to the said latch, the adjacent end of the stem part of the said housing being bored and slotted to receive a key and means in connection with the said movable member for operating it to project 60 the latch by means of the inserted key substantially as described.

2. A keyhole-guard consisting of a housing having substantially the form of the bit and adjacent parts of the stem of the lock-key, a latch 65 9 having projection 9² mounted to slide in said housing and adapted to be projected out of the same at the back of the bit part of the housing, a diagonal groove 10 in the front part of said latch, a slide 11 having downwardly-extending pin to engage said groove, a series of tumblers to control the movement of said slide, the adjacent stem part of the housing being bored and slotted to allow a key 70 access to the said tumblers to operate the latch 75 in the manner and for the purpose substantially as described.

In testimony whereof I affix my signature in presence of two witnesses.

JOSEF KOHOUSEK.
